Specification for Design.

Patented Nov. 27, 1917.

Application filed September 22, 1917. Serial No. 192,818. Term of patent 14 years.

To all whom it may concern:

Be it known that I, Bjarne Falkenberg, a citizen of Ontario, in the county of San Bernardino and State of California, have invented a certain new, original, and ornamental Design for Casing and Standards of Electric Heaters and the like, of which the following is a specification, reference being had to the accompanying drawing, forming a part hereof.

Figure 1 of the drawing is a front elevation of a casing and standards of electric heaters and the like embodying the present invention.

Fig. 2 is a side elevation thereof.

I claim—

The ornamental design for a casing and standard of electric heaters and the like as shown.

Bjarne Falkenberg.
